BRASSIERE

Filed April 25, 1946

UNITED STATES PATENT OFFICE

2,483,272

BRASSIÈRE

Harry Gluckin, New York, N. Y., assignor to The
Gluckin Corporation, New York, N. Y., a corporation of New York

Application April 25, 1946, Serial No. 664,929

2 Claims. (Cl. 2—42)

1

This invention relates to garments generally classified as brassières. More particularly, the invention deals with an improved garment of this type and kind having means comprising a one-piece frame or supporting element for supporting the breast cups or pockets upon the body of the wearer. Still more particularly, the invention deals with garments of the type and kind under consideration, wherein the pockets are formed from single pieces of material having chambers or channels at peripheral edges thereof for reception of curved or substantially horseshoe-shaped frame parts, said parts being joined centrally by a yieldable bridging portion.

The novel features of the invention will be best understood from the following descriptions, when taken together with the accompanying drawing, in which certain embodiments of the invention are disclosed and, in which, the separate parts are designated by suitable reference characters in each of the views and, in which:

Fig. 1 is a front perspective view of a brassière made according to my invention.

Fig. 2 is a view similar to Fig. 1 showing another form of brassière with parts of the construction broken away.

Fig. 3 is a rear view of another form of brassière which I employ with parts broken away; and

Fig. 4 is a section on the line 4—4 of Fig. 1.

While my invention is designed primarily for use in connection with what is termed brassières, the reinforcing and supporting element may constitute a part of a garment of any type and kind having breast receiving and supporting pockets or portions, the garment being fashioned to provide some means to support the element or loop or horseshoe-shaped portions of the element against displacement from the garment. Further, the element normally supports the front pocket or cup portion of the garment normally in a relatively straight position, the element being flexed or put under tension when the garment is mounted upon the body of the wearer.

In Fig. 1 of the drawing, I have shown at 10, 10' two similar pocket or cup portions of a brassière, being preferably formed from a single sheet of material, joined by a dart as, for example, at 11 on the cup 10 to give breast contour thereto. Upper and side edges of the pockets 10, 10' have circumferential chambers or channels, as indicated at 12 in Fig. 4 of the drawing, in which are disposed loop portions 13, 13' of a reinforcing element or frame 14. The loop portions 13, 13' are substantially horseshoe-shaped in form and terminate at their outer free ends in inturned

2

portions, for example, at 15 on the loop 13 of Fig. 1. The other end portions have elongated loop portions 16, 16', which are joined by an upwardly extending spring loop 17, the latter being preferably covered by a sleeve or tubing 18 to prevent direct contact of the wire with the body of the wearer.

Inner adjacent ends of the chambers 12 extend to the lower edges 19, 19' of the cups or pockets and adjacent said ends are openings 20, 20' which open through the inner surface of the cups to facilitate insertion and removal of the elongated loops 16, 16' in coupling and uncoupling the reinforcing element 14, particularly in laundering the garment.

Extending from the outer sides of the lower edges 19, 19' are side and back straps, one of which is shown at 21 at the left of Fig. 1 of the drawing and other downwardly inclined straps 22 are also employed, the latter joining the straps 21 at the back of the garment and these straps have suitable couplings, such, for example, as the couplings shown in Fig. 3 of the drawing. These couplings are not shown in Fig. 1, as this particular feature of the brassière is common and well known in the art.

Inner adjacent sides of the cups 10, 10' are also preferably joined by tie-ribbons 23, 23' for drawing the cups or pockets toward each other. When these ribbons are not used, they may be tucked upon the inner faces of the cups or pockets.

Considering Fig. 4 of the drawing, it will also be apparent that the edge portions of the cups or pockets are preferably faced with a soft cushioning strip or pad, as at 24, 24', which extends onto the inner face of the cups and cushions the engagement of the element 14 with the body of the wearer.

In Fig. 2 of the drawing, I have shown a modification, in which two similar cups 25, 25' are employed and substantially similar to the cups 10, 10' with the exception that the lower portions of the cups are integrally joined by a band or strap member 26. This strap member extends to the sides and back of the garment and again has detachable couplings, similar to those shown in Fig. 3.

In Fig. 2, instead of using the independent angular straps, as at 22, the side portions of the brassière have substantially V-shaped or triangular band portions, one of which is shown at 27, which extend from the central portion of the cups or pockets to the band 26.

In Fig. 2, a reinforcing element or frame 28

is employed which differs from the frame 14, primarily in having the elongated loop ends 29, 29' thereof joined by a downwardly extending loop portion 30, which is otherwise similar to the loops 17.

At the left of Fig. 2 is shown one of the openings 31, similar to the openings 20, 20'.

In Figs. 1 and 2, as well as in Fig. 3, the outer ends of the frames all extend to the waist band or lower portion of the brassière. For example, in Fig. 2, the incured end of the frame loop 32 is indicated at 33 and at 32' is shown part of the loop of the cup 25'. With the construction shown in Fig. 2, shoulder straps 34, 34' may also be employed. These straps have, at their ends, hook members 35, 35' and 36, the strap end 34' being broken away. These hook ends are adapted to engage eyes or similar members on the upper edge portions of the cups 25, 25' and on the band 26 or the rear portion thereof. By making the shoulder straps quickly attachable and detachable, the garment may be worn as a garment or shoulder strap type of garment adapting the same for two independent and distinct uses.

In Fig. 3 of the drawing, I have shown a rear view of another form of brassière which I employ, comprising two similar cups 31, 37', similar, in all respects, to the cups 25, 25', and integrally joined by a band 26', similar to the band 26. It will be noted, however, that the V-shaped or triangular side extensions, as at 27 of Fig. 2, are not employed. In Fig. 3, 28' represents a frame, identical with the frame 28 of Fig. 2, the openings for admission to the peripheral chambers of the pockets being indicated at 31' and 31''. With this construction, shoulder straps 38, 38' are employed, similar to the shoulder straps 34, 34', the same being detachably coupled in the manner set forth in connection with the structure shown in Fig. 2.

In Fig. 3, I have shown at 39, 39', the rear end portions of the strap 26' and which may be also considered as rear end portions of the strap 26 and the strap 21. One strap, for example, the strap 29 has, on its inner surface, a hook member 40 adapted to engage one of a number of eyes 41 on the strap end 39'. In size adjustment of the brassière upon the body of the wearer and one of the straps, for example, the strap 39 may have elastic properties, particularly in the form of garment shown in Figs. 2 and 3. However, with the garment, as shown in Fig. 1, the spring properties of the loop 17 is sufficient for yieldable support of the garment upon the body of the wearer. It will also be understood that the horseshoe-shape of the loops of the reinforcing elements or frames normally tension each pocket to expand the cups, so that, when the breasts enter the cups, the frame is tensioned inwardly, at least to a slight extent. This aids in supporting the frame snugly upon the body of the wearer with the breasts in upward youthful position.

Having fully described my invention, what I claim as new and desire to secure by Letters Patent is:

1. A brassière of the class described compris-

ing two similar cups, each comprising a single piece of fabric shaped to form the cup portion, said cup portions having rounded upper edges, upper and side edges of each cup portion having a longitudinal channel, adjacent sides of the channels of said cup portions having openings adjacent channel ends, a one-piece supporting element detachable with respect to the channels through said openings, said element having substantially horseshoe-shaped, curved loop portions fitting in the channels of said cup portions, a member bridging the curved loop portions intermediate said cup portions in coupling loops extending into said channel ends, said member yieldably joining said cup portions, means attached to outer sides of the cup portions for supporting the garment upon the body of the wearer, said bridging member comprising a spring loop disposed freely between adjacent sides of the cup portions, a one-piece band extending along lower sides of the cup portion and joining adjacent edges of said cup portions, a pair of shoulder straps, and means detachably coupling the shoulder straps with upper central portions on said cup shaped portions and said first named means.

2. A brassière of the class described comprising two similar cups, each comprising a single piece of fabric shaped to form the cup portion, said cup portions having rounded upper edges, upper and side edges of each cup portion having a longitudinal channel, adjacent sides of the channels of said cup portions having openings adjacent channel ends, a one-piece supporting element detachable with respect to the channels through said openings, said element having substantially horseshoe-shaped, curved loop portions fitting in the channels of said cup portions, a member bridging the curved loop portions intermediate said cup portions in coupling loops extending into said channel ends, said member yieldably joining said cup portions, a band attached to lower sides of the cup shaped portions and extending to the sides and back of the garment, means at the ends of said band for detachably and adjustably coupling the same, a pair of shoulder straps, and means at the ends of said straps and on said band and cup shaped portions for detachably coupling the straps with the garment.
